UNITED STATES PATENT OFFICE.

EDWARD A. HAIGHT, OF SHALERSVILLE, AND DELBERT WILLIAMS,
OF CLEVELAND, OHIO.

BED-BOTTOM.

SPECIFICATION forming part of Letters Patent No. 272,956, dated February 27, 1883.

Application filed November 1, 1882. (No model.)

To all whom it may concern:

Be it known that we, EDWARD A. HAIGHT, of Shalersville, Portage county, Ohio, and DELBERT WILLIAMS, of Cleveland, Ohio, have invented a new and useful Improvement in Bed-Bottoms, of which the following is a specification.

This invention relates to bed-bottoms in which the coil-springs are rectangular at the top and are connected at the sides and ends of the bed-bottom with two torsion-springs, each of which extends the length of one side and half across the ends of the bed.

In the drawings forming a part of this specification, Figure 1 is a plan. Fig. 2 is a side elevation, and Fig. 3 is an end elevation.

The coil wire springs *a* are attached at the bottom to slats *b*, and are of the usual construction for bed-bottoms, except that they are of rectangular form at the top. They are connected at their corners with each other, and with the torsion-springs *c c* at the ends and sides of the bed-bottom by wire hooks *e*. Their rectangular form prevents wire hooks *e* from slipping on them and becoming dislodged from them. Each of the springs *c c* extends along the side of the bed and half across its ends at the top of the coil-springs *a*, to which they are fastened by hooks *e*. Each spring *c* is made of spring-wire, its ends being attached to the outer slats, *b*, from whence it inclines upward near to the center line lengthwise of the bed, and nearly to the top of coil-springs *a*, and then extends lengthwise of the bed to the outer side of the end rows of coil-springs *a*, and half across each end of the bed and along its side. Thus the two springs *c c* substantially surround the bed level with the tops of coil-springs *a*, to which they are attached by wire hooks *e*, to prevent lateral movement of coil-springs *a* and keep them upright. Across the bed, at its head, the two end rows of coil-springs *a* are higher than the others, the end row being the highest, and the springs *c c* are correspondingly bent upward at the sides, as shown in Fig. 2, to conform to the level of the tops of the coils *a*. Near each end of the bed the wires *s s'* are attached to inner slats, *b*, and have their outer ends hooked to springs *c c* at the side of the

bed, forming auxiliary springs, and also preventing the springs *c c* from springing outward and away from each other. Springs *s s'* are hooked together between the center slats, *b*, for convenience in separating the bed-bottom into two sections lengthwise through the center. For the same purpose cross-bars *d d'*, to which slats *b* are attached, are in two sections. Wire hooks *e*, connecting coil-springs *a*, are twisted together at their centers lengthwise of the bed, to prevent them from slipping on each other where they cross. The central row of wire hooks *e* lengthwise of the bed cross each other without being twisted, for the purpose of facilitating the operation of unhooking them from coil-springs *a* when dividing the bed into two separate sections. If a sectional bed-bottom be not desired, the wires *s s'* may be of one piece, instead of two pieces hooked together in the center, and cross-bars *d d'* may also be of one piece.

We claim as our invention—

1. In a spring bed-bottom, the coil-springs *a*, being of a rectangular form at the top, and connected diagonally at their corners with hooks *e*, in combination with torsion-springs *c c*, connected at the sides and ends of the bed-bottom with the outer coil-springs at their corners, substantially as described.

2. The torsion-springs *c c*, attached to slats *b*, and each extending substantially half around the bed, and connected with coil-springs *a*, substantially as described.

3. The cross-wires *s s'*, in combination with and attached to slats *b*, and torsion-springs *c c*, substantially as described.

4. The coil-springs *a* at and near the head of the bed being higher than the level of the tops of the other coil-springs, in combination with springs *c c*, bent upward near the head, to conform to the extra height of the coil-springs at the head, with which they are connected by hooks *e*, substantially as described.

EDWARD A. HAIGHT.
DELBERT WILLIAMS.
